US00D876990S

(12) **United States Design Patent** (10) **Patent No.:** **US D876,990 S**
Yoshitomi et al. (45) **Date of Patent:** **** Mar. 3, 2020**

(54) **MOTORCYCLE AND/OR REPLICA THEREOF**

(71) Applicant: **HONDA MOTOR CO., LTD.**, Tokyo (JP)

(72) Inventors: **Hiroki Yoshitomi**, Wako (JP); **Yoshiyuki Ishiguri**, Wako (JP)

(73) Assignee: **HONDA MOTOR CO., LTD.**, Tokyo (JP)

(**) Term: **15 Years**

(21) Appl. No.: **29/671,763**

(22) Filed: **Nov. 29, 2018**

(30) **Foreign Application Priority Data**

May 30, 2018 (JP) 2018-011843
(51) **LOC (12) Cl.** **12-11**

(57) **CLAIM**

The ornamental design for a motorcycle and/or replica thereof, as shown and described.

DESCRIPTION

FIG. 1 is a front elevation view of a motorcycle and/or replica thereof showing our new design;

FIG. 2 is a rear elevation view thereof;

FIG. 3 is a top plan view thereof;

FIG. 4 is a right side elevation view thereof;

FIG. 5 is a left side elevation view thereof;

FIG. 6 is a front and right side perspective view thereof;

FIG. 7 is a front and left side perspective view thereof;

FIG. 8 is a rear and right side perspective view thereof; and,

FIG. 9 is a rear and left side perspective view thereof.

The broken lines in the drawings illustrate portions of the motorcycle and/or replica thereof that form no part of the claimed design.

1 Claim, 5 Drawing Sheets
